UNITED STATES PATENT OFFICE.

THEODORE RAY MINERT, OF MILWAUKEE, WISCONSIN.

PUMP-OPERATING MECHANISM.

1,344,056.

Specification of Letters Patent. Patented June 22, 1920.

Application filed February 24, 1919. Serial No. 278,829.

To all whom it may concern:

Be it known that I, THEODORE R. MINERT, a citizen of the United States, residing at Milwaukee, in the county of Milwaukee and 5 State of Wisconsin, have invented a new and useful Improvement in Pump-Operating Mechanism, of which the following is a specification.

The object of this invention is the production of a simple and inexpensive pump head which will pump water or other liquid from deep wells or compress or exhaust air or gas in substantially a continuous stream. A further object is the production of an 10 assemblage of parts which is thoroughly lubricated and less liable to get out of order than with pump heads heretofore produced.

A further object is to evenly distribute the pumping force on the parts of the head 15 so that there is no side draft which would cramp the mechanism and increase the amount of energy used for raising a given amount of liquid.

With these and other objects in view, my 20 invention comprises the features of construction and combination of parts herein-after more particularly described and claimed.

In the accompanying drawings forming 25 part of this specification, Figure 1 is a side elevation of my invention; Fig. 2 is a rear elevation; Fig. 3 is a front elevation; Fig. 4 is a plan view; Fig. 5 is a plan of the main driving gears and cranks; Fig. 6 is a 30 plan of the lower cross head; Fig. 7 is an elevation of a detail of part of the outside well rod, the bearing roller being shown in section; Fig. 8 is a plan of the roller bearing on the crank shaft; Fig. 9 is a section taken on the line 8—8 of Fig. 8; Fig. 10 is an elevation showing a different method of 35 arranging the bell cranks for medium duty pumps; Fig. 11 is a plan of the gear and crank for the construction shown in Fig. 40 10; Fig. 12 is a side elevation of the crank arm of an alternative construction, the main head shaft and pin connection being shown in section; Figs. 13 and 14 are detail views 45 of wind mill connections for use in connection either with the preferred or alternative 50 construction; Figs. 15, 16 and 17 are elevations of another alternative construction showing my invention arranged for use for operating a farm pump having two sepa-

rate cylinders; and Fig. 18 is a section taken 55 on the line 15—15 of Fig. 15.

In the drawings let 20 and 21 indicate a pair of outside bell cranks which are journaled to rotate at their angles on a shaft 23 which is secured in the upright sides 24 60 and 25 of a supporting frame 26. These bell cranks are substantially similar in size and construction and the forward ends of their upper arms are attached by pivots 27 to outside connecting rods 28 and 29 and 65 their lower ends connected to the free ends of the crank members 30 of the unitary pair of gears 31 and connecting crank member 32. The connecting rods 28 and 29 are secured to the lower cross head 33, which is 70 slidably mounted to move vertically on the guide rods 34 and connected by the bearing 35 to the upper end of the outside well rod 36 which is connected at the bottom to an outside plunger in the well cylinder or casting 37.

The shaft members 38 are co-axial with the axes of the gears 31 and are journaled in the side members 24 and 25 of the frame 26 with the gears arranged between said 80 sides. Disposed above said gears and journaled in said sides is a main drive shaft 39 which carries a main drive pulley 40 and a pair of pinions 41, the teeth of which mesh with the teeth of said gears to revolve the 85 crank elements 30. The lower arms of the bell cranks are formed with longitudinal channels 70 over which are secured by bolts 43 longitudinal bearing plates on which travel roller bearings 45 (see Figs. 1, 8 and 90 9) which are movably secured over the bearing plates 44 by yokes 46 extending across the channels 70 and below said plates. The anti-friction roller bearings are journaled on the crank pin 30, and as the crank elements 95 revolve the bell cranks are rocked to reciprocate the pair of outside well rods and their connected plungers, simultaneously, by a combined sliding and rolling movement between the bell cranks and the rotary driving crank elements. This operation is 100 smooth and noiseless with little friction.

Arranged between the gears 31 and pinions 41 is a center bell crank 42' which also is journaled at its angle freely on the shaft 105 23. The forward upper free arm of this bell crank is connected by the link 43' to the cross head 35 which in turn is connected

to the center connecting rod 22, said cross head sliding vertically on the pair of guide rods 34. The guide rods are supported in alinement with the center of the well rigidly 5 in vertical position by the base 48 of the frame and the transverse support 47 which is carried by the side members 24 and 25. The base 48 forms a cover and is bolted to the well casing 37.

10 The upper cross head 35 is anchored to the upper end of the inside well rod 22 which slides downwardly and freely through the outside well rod 36 in the lower cross head 33 and well casing. The outside well rod also slides freely through a gland 49 placed in the cover and supporting element 48.

15 The lower arm of the center bell crank is reciprocated by a roller bearing 50 also 20 similar to the construction shown in Figs. 8 and 9, which is journaled on the crank member 32 and engages over a bearing plate 51 as with bearings 45 and plates 44. By this construction the center bell crank 42' 25 and rod 22 are reciprocated by a combined turning and sliding movement of the crank 32 and its anti-friction bearing 50.

20 Secured upon the frame below the gears so that the latter will dip into oil contained 30 therein to be lubricated thereby, is an oil pan 52.

25 The cranks produce an overlapping stroke and therefore assist in pumping a continuous stream, due to the fact that two tangents drawn from point 23 to opposite sides of the crank circle divide the crank circle into two unequal portions, so that the stroke in one direction is produced by more than a half revolution of the crank pin, and 35 in the opposite direction by less than a half revolution of the crank pin. As this is true of each of the diametrically disposed crank pins, the two actuated pistons overlap at the ends of their respective strokes. The degrees of overlapping may be varied by varying 40 the diameter of the crank circle, or by varying the distance of the crank shaft from shaft 23. During the operation of the pump head the bearing rollers roll on the finished

45 bearing bars 44 and 51 and reduce friction to a minimum. As a safeguard, the bars are held in contact with the rollers by their yokes. The cross head 33 is shown split (see Fig. 6) being formed with a bearing 50 cap 53 removably secured by bolts 54. By removing said bolts and cap the outside well rod 36 is released and the pump head may be pushed back away from over the well after the inside pump rod is also disconnected.

55 60 When desired, the bell cranks can be connected to a wind mill for operation by a connecting rod 55 sliding in a guide 56. The center unit or upper cross head can also be connected to a wind mill reciprocating shaft 65 such as 55 to actuate the inner pump ele-

ment in the pump casing. The above mechanism is adapted for heavy duty or large size machines. For smaller machines the modification shown in Figs. 10, 11 and 12 can be used to advantage. In this construction the bell crank 57 and lever arm 58 are keyed to shaft 59 at 60 and 61 and in this case the shaft 59 will have to rotate in the frame. The other parts are substantially the same as in the construction shown in Fig. 1. The crank shaft 70 and gear 71 are of simple type. In Figs. 15 to 18 inclusive the construction is adapted for small wells, using two separate and distinct cylinders and pump rods. Two bell cranks 62 and 63 80 operated by a single crank shaft 65 are employed, the crank members being spaced at 180 degrees as in the preferred construction. The cranks have sliding bearings 66 which permit the revolution of the crank shaft to reciprocate the bell cranks and connected pump shafts 68 and 69.

85 By this arrangement and construction, the use of connecting rods guide rods and cross heads are obviated since the plunger rods do not work in stuffing boxes at the top of the well and the slight deviation in alinement does not materially decrease efficiency in operation.

90 Among the advantages attained by my invention are: a steady stream of water or other liquid is produced as the pump has no dead center at the end of the stroke and one plunger is always moving upward; the strain between the two plunger rods is carried direct through one crank shaft or gear and crank, thus avoiding excessive wear and "back lash" of the pinions as in prior devices; the pump is compact, requires less space than other pumps and it is low so that strains are reduced; it requires less material to build; it is more efficient and quiet in operation, the roller bearings and moving parts being saturated with oil continuously; the loads are evenly distributed to avoid sidestrains; and the pump head can be easily disconnected and removed from the pump rods.

95 In accordance with the patent statutes I have described the principles of operation 115 of my invention together with the apparatus which I now consider to be the best embodiment thereof but I desire to have it understood that the construction shown is only 120 illustrative and that the invention can be carried out by other means and applied to uses other than those set forth within the scope of the following claims.

125 Having described my invention, what I claim is new and desire to secure by Letters Patent is:

1. Pumping apparatus, comprising, in combination, a pair of plunger pump shafts to be reciprocated successively, a crank shaft journaled to revolve, having a pair of 130

diametrically arranged crank pins, rocking bell cranks arranged on an axis to swing and reciprocate successively, one arm of each crank being linked to one of said pump 5 shafts and the remaining arms bearing on said crank at points diametrically opposite, said bell cranks and crank pins being arranged so that two tangents drawn from said axis to opposite sides of the crank 10 circle, divide the crank circle into substantially two unequal portions, whereby the stroke of each pump shaft in one direction is produced by more than a half revolution of the crank shaft, and in the opposite direction by less than a half revolution of the crank shaft, to pump a continuous stream.

2. Pumping apparatus, comprising, in combination, a pair of plunger pump shafts to be reciprocated successively, a crank shaft 20 journaled to revolve having a pair of diametrically arranged crank pins, a plurality of rocking bell cranks coaxially arranged on an axis above said crank shaft to under swing and reciprocate successively, one arm 25 of each crank being linked to one of said pump shafts and the remaining arms bearing on said crank pins, said bell cranks and crank pins being arranged so that two tangents drawn from said axis to opposite sides 30 of the crank circle, divide the crank circle into substantially two unequal portions, whereby the stroke of each pump shaft in one direction is produced by more than a half revolution of the crank shaft, and in the opposite direction by less than a half revolution of the crank shaft, to pump a continuous stream.

3. Pumping apparatus, comprising, in combination, a pair of plunger pump shafts 40 to be reciprocated successively, a crank shaft journaled to revolve having a pair of diametrically arranged crank pins, a plurality of rocking bell cranks coaxially arranged to swing and reciprocate successively, one arm of each crank being linked to one of said pump shafts and the remaining arms being joined on their backs to said crank pins by antifriction sliding pivot 45 connections, said bell cranks and crank pins being arranged so that two tangents drawn from said axis to opposite sides of the crank circle, divide the crank circle into substantially two unequal portions, whereby the stroke of each pump shaft in one direction is produced by more than a half revolution of the crank shaft, and in the opposite direction by less than a half revolution of the crank shaft, to pump a continuous stream.

4. Pumping apparatus, comprising, in combination, a pair of plunger pump shafts 60 to be reciprocated successively and substantially vertically, a substantially horizontal journaled crank shaft having a pair of diametrically arranged crank pins, a plurality 65 of rocking bell cranks coaxially arranged on

a substantially horizontal axis above said crank shaft to under swing and reciprocate successively, one arm of each crank being linked to one of said pump shafts and the remaining arms being journaled to said 70 crank pins by antifriction sliding pivot connections, means for driving said crank shaft, and a pan arranged to hold lubricant into which said driving means and bell cranks are adapted to dip to lubricate moving connections, said bell cranks and crank pins being arranged so that two tangents drawn from said axis to opposite sides of the crank circle, divide the crank circle into substantially two unequal portions, whereby the stroke of each pump shaft in one direction is produced by more than a half revolution of the crank shaft, and in the opposite direction by less than a half revolution of the crank shaft, to pump a continuous stream.

5. Pumping apparatus, comprising, in combination, a pair of plunger pump shafts to be reciprocated successively, a horizontal crank shaft journaled to revolve having diametrically arranged crank pins, three rocking bell cranks hung from an axis above said crank shaft and adapted to swing two in one direction together and the other in the opposite direction between said pair, a 90 head frame connected to one of said shafts, one arm of said single bell crank being connected to the other pump shaft, one arm of each of the pair of bell cranks being coupled to said head frame and the remaining 95 arms of all of said bell cranks being movably joined to said crank pins at points diametrically opposite, said bell cranks and crank pins being arranged so that two tangents drawn from said axis to opposite sides of the crank circle, divide the crank circle into substantially two unequal portions, whereby the stroke of each pump shaft in one direction is produced by more than a half revolution of the crank shaft, and in the opposite direction by less than a half revolution of the crank shaft, to pump a continuous stream.

6. Pumping apparatus, comprising, in combination, a frame, a pair of plunger 115 pump shafts disposed adjacent to said frame to be reciprocated successively, a crank shaft journaled to revolve in said frame having diametrically arranged crank pins, a plurality of rocking bell cranks coaxially arranged to swing from an axis above said shaft on said frame, gearing journaled on said frame for driving said shaft, a head frame coupling a pair of said bell cranks to one of said pump shafts and a 120 link coupling the remaining bell crank to the remaining pump shaft, said single bell crank being arranged between the pair of bell cranks and all of said bell cranks being slidably and pivotally joined to said crank 130

pins, the points of said connections by said single bell crank and pair of bell cranks being diametrically opposite, said bell cranks and crank pins being arranged so that two tangents drawn from said axis to opposite sides of the crank circle, divide the crank circle into substantially two unequal portions, whereby the stroke of each pump

shaft in one direction is produced by more than a half revolution of the crank shaft, ¹⁰ and in the opposite direction by less than a half revolution of the crank shaft, to pump a continuous stream.

In testimony whereof I have signed my name to this specification.

THEODORE RAY MINERT.
